UNITED STATES PATENT OFFICE.

VALENTINE M. KUTSCHA, OF SCOTCH PLAINS, NEW JERSEY.

BALANCE-CONTROLLER FOR AEROPLANES.

992,678.

specification of Letters Patent. Patented May 16, 1911.

Application filed January 9, 1911. Serial No. 601,627.

To all whom it may concern:

Be it known that I, VALENTINE M. KUTSCHA, a citizen of the United States, residing at Scotch Plains, in the county of Union and State of New Jersey, have invented certain new and useful Improvements in Balance-Controllers for Aeroplanes, of which the following is a specification, reference being had therein to the accompanying drawing.

This invention relates to flying machines of the aeroplane type, and the principal object of the same is to provide novel means for automatically operating the main plane thereof so that said plane will be caused to assume a proper supporting position in the event of the same being deflected by air currents or the like.

In carrying out the objects of the invention generally stated above it will be understood, of course, that the essential features thereof are necessarily susceptible of changes in details and structural arrangements, one preferred and practical embodiment of which is shown in the accompanying drawings, wherein:

Figure 1 is a perspective view of the improved flying machine. Fig. 2 is a view in end elevation, the body being omitted. Fig. 3 is a top plan view thereof, partly broken away, and shown partly in section. Fig. 4 is a fragmentary detail view of one of the braces for the main plane. Fig. 5 is a fragmentary view in elevation showing one of the standard braces. Fig. 6 is a transverse sectional view taken on the line 6-6, Fig. 5.

Referring to the accompanying drawings by numerals, it will be seen that the improved air ship comprises a body 6 provided with the wheels 7 for use on land; the propeller 8; the rudder 9, and rear plane 10, all of which may be of the usual or any preferred construction.

Body 6 is provided with forward and rear vertically arranged sets of uprights 11, each set carrying an elongated and slightly arched supporting bar 12 that extends transversely of and projects well beyond the longitudinal sides of the said body 1. The outer ends of the bars 12 are bifurcated to provide the pivot ears 13 in which the adjusting arms 14 are pivotally mounted. The lower ends of said arms 14 project beyond the ears 13 and have cable or other flexible connections 15 with intermediate portions of bars 12 to limit their inward pivotal

movements. The upper ends of arms 14 are equipped with rollers 16 and at intermediate points, said arms 14 have spring connections 17 with the bars 12 to yieldably oppose outward pivotal movements of said arms.

The bars 12 carry a pair of oppositely disposed centrally located vertical standards 18 which are equipped with aligned openings 19 through which a rocker shaft 20 extends. The ends of said shaft 20 are journaled in bearing openings formed through the bars 12. A main plane 22 is fast on shaft 20 and its free ends overhang the rollers 16 of arms 14. The upper ends of standards 18 are connected by a guide bar 23 and tension braces 24 which connect opposite end portions of the upper surface of plane 22 are slidably transversely across said bar 23. The braces 24 have end springs 25 that are connected to the ends of the plane 22 and intermediate springs 26 which are disposed on opposite sides of the bar 23 and are primarily intended to prevent ends of said plane sagging.

The enlarged base of the rear standard 18 is provided with a pair of spaced parallel laterally projecting, outwardly extending stub shafts 27 upon which the semicircular bases 28 of the oppositely projecting supporting arms 29 are pivotally mounted. Said bases 28 are provided with meshing peripheral teeth 30 which cause the arms to move toward each other when rocked in one direction and away from each other when rocked in an opposite direction. The arms 29 are bent in a forward direction so that they project beneath the plane 22 and said arms have spring connections 31 with the base of the rear standard that exerts a lifting tension on the free ends of said arms so that said free end will engage the under-surface of the plane 22 at opposite sides of shaft 20 and thereby normally retain the plane 22 in a horizontal position.

Arched braces 32 are fastened to the standards 18 by the staples 33 or other suitably fastening means, and the free ends of said braces 32 are looped, or otherwise fastened to the bars 12, as indicated by the numeral 34 in Figs. 5 and 6 of the accompanying drawings. The oppositely disposed outer ends of the bars 12 are connected by the rods 35 which pass through the ears 13 and serve as pivots for the arms 14.

From the foregoing it will be clear that

the plane 22 is normally supported in a horizontal position by the arms 29. The plane being pivotally supported by shaft 20, it will be seen that in the event of said plane being rocked by air currents or other pressure, one of the arms 29 will be depressed against the tension of its spring 31 and the plane will be caught by the end rollers of one set of the arms 14. The arms 14 having 10 spring connections with the bars 12, will oppose further movement of the plane and when the rocking pressure is removed from said plane, the tension of the springs of arms 14 and arms 29, cause said arms to automatically restore the plane to a supporting position.

It is to be understood, of course, that the type of body, propellers, wheels, rear plane, and rudder are conventional showings and 20 that the same form no part of this invention, the invention primarily residing in the pivotally mounted main plane, the supporting means and the means for automatically restoring the plane to a supporting position.

25 What I claim as my invention is:—

1. An air ship comprising a body, spaced parallel vertically arranged supports carried thereby, a plane pivotally connected to said supports, transversely arranged bars 30 carried by said supports, means pivotally connected to one of said supports for normally retaining said plane in a supporting position, and means pivotally connected to said bars for restoring said plane to a supporting position.

2. An air ship comprising a body, spaced parallel transversely arranged bars carried thereby, a main plane, means for pivotally supporting said plane above said bars, means 40 for normally retaining said plane in a supporting position, and means carried by the ends of said bars for automatically restoring said plane to a supporting position.

3. An air ship comprising a body, bars 45 carried thereby, oppositely disposed standards carried by said bars, a rocker shaft carried by said standards, a plane fast on said shaft, means carried by one of said standards for normally retaining said plane in a supporting position, and means carried by said bars for automatically restoring said plane to a supporting position.

50 4. An air ship comprising a body, transversely arranged parallel bars carried there-

by, a plane pivotally supported above said bars, means for normally retaining said plane in a supporting position, and spring-actuated arms pivotally connected to said bars for restoring said plane to a supporting position.

5. An air ship comprising a body, standards carried thereby, a supporting plane pivotally connected to said standards, oppositely projecting arms for normally retaining said plane in a supporting position, said arms have their bases pivotally connected to one of said standards, said bases having teeth in mesh to cause said arms to move in unison, springs connecting said arms to said standards, and means for automatically restoring said plane to a supporting position.

6. An air ship comprising a body, parallel transversely arranged bars carried thereby, a supporting plane pivotally supported above said bars, means for normally retaining said plane in a supporting position, arms pivotally connected to the ends of said bars, rollers carried thereby for engaging the ends of the plane, means for limiting the pivotal movements of said arms in one direction, 80 and springs connecting said arms to said bars for causing said arms to restore said plane to a supporting position.

7. An air ship comprising a body, standards carried thereby, a plane pivotally connected to said standards, means for normally retaining said plane in a supporting position, means for restoring said plane to a supporting position, a guide bar connecting the upper ends of said standards, and tension 90 braces slideable over said guide bar and having end springs connected to the ends of said plane and intermediate springs disposed on opposite sides of said bar.

8. An automatically acting mechanism for 95 supporting planes of air ships comprising a pivotally mounted plane, a pair of pivotally mounted arms for normally holding said plane in a supporting position, and oppositely disposed sets of arms for engaging the 100 ends of said plane when tilted to restore the plane to a supporting position.

In testimony whereof I hereunto affix my signature in presence of two witnesses.

VALENTINE M. KUTSCHA.
